UNITED STATES PATENT OFFICE

KITARO KATO, OF TOKYO, JAPAN

WINDOW

Application filed June 25, 1927. Serial No. 201,455.

My invention relates to improvements in windows and more particularly to windows of the kind comprising double-hung sashes.

One object of my invention is to provide means whereby a plurality of sashes can readily slide up and down either individually or jointly.

Another object of my invention is to obtain means for holding all of the plurality of sashes or either one of them at any desired heights, whereby the window may positively assume any desired positions of the double-hung sashes.

A further object of my invention is to obtain means for providing counter-weights for the two sashes combined and also providing guide means for sash-cords, which guide means may function as either movable or stationary.

A still further object of my invention is to provide means for guiding the counter-weight and also for preventing it from any lateral movement, together with means for releasably restraining the counter-weight from its vertical movements to hold it at any desired height.

There are other objects and particularities of my said invention, which, together with the foregoing, will appear in the following descriptions, with reference to the accompanying drawings, wherein:

Fig. 1 is an inside elevational view of my window, partly in section and partly broken away.

Fig. 2 shows a sectional elevation taken at line II—II in Fig. 1.

Fig. 3 is a view similar to Fig. 2, showing another position of the double-hung sashes.

Fig. 4 is a similar view to Fig. 2, and shows the uppermost positions of both of the sashes.

Fig. 5 is a sectional plan view, in part, taken at line V—V in Fig. 4.

Fig. 6 is a plan view partly in section showing the construction and arrangement of means used in the embodiment for releasably restraining the sash-cord and the counter-weight from their vertical movements.

Fig. 7 is a front elevational view partly in section of the construction shown in Fig. 6.

Figs. 8 and 9 are enlarged detailed views of a part of means shown in Figs. 6 and 7, in front elevation and plan, respectively.

Fig. 10 shows a sectional plan taken at line X—X in Fig. 8.

Fig. 11 is an elevational view of the counter-weight member, partly in section.

Fig. 12 is a sectional plan view taken at line XII—XII in Fig. 11.

Fig. 13 shows a modified construction of means for releasably holding the wire rope from its travelling.

Fig. 14 shows, somewhat diagrammatically, a modification in part of my window controlling means.

Fig. 15 is a sectional view taken at line XV—XV in Fig. 14.

In practising my invention, I provide a pair of sashes, each slidably guided in suitable grooves at its sides in the framework of window, and a sash-cord secured at the ends to the sides of the respective sashes, forming an open loop ending at the respective sashes. The cord extends past a pair of stationary guide rollers mounted in the upper portion of the framework and also a movable guide roller intermediate the two stationary rollers. The movable roller is mounted on a weighted member, which is movable up and down within a side chamber in the framework, and is adapted to be releasably restrained from the movement, at will.

In order to facilitate a better understanding of my invention, the following descriptions are given with reference to the drawings.

Referring particularly to Figs. 1 to 7, a window embodying my invention comprises, in general, a rectangular framework 1, having a plurality of longitudinal grooves 2 in each of its vertical sides, and an inner and an outer sash 3 and 4, for holding window glasses therewith and adapted to slide up and down along the vertical grooves 2 with their vertical side edges guided thereby.

At the top portion of each vertical side of the framework 1, there are provided three stationary pulley or guide rollers 5, 6 and 7. The roller 6 forms a cooperating pair of roll-

ers with another stationary guide roller 8, and a wire rope 9 is stretched between the pair of rollers 6 and 8, carrying a weighted member 10, to which the rope ends are secured by suitable means as shown at 11 and 12. The 5 rollers may have peripheral grooves. The counter-weight 10 is adapted to travel up and down within a vertical side chamber formed in the framework 1 behind its grooved side. Another rope or sash-cord 13 is also provided 10 extending between the inner and outer sashes past the stationary rollers 5 and 7, and a movable roller 14 mounted on the counter-weight 10.

15 Each rope 9 is operatively engaged by a restraining device 15 conveniently arranged in the lower portion of each side chamber, for releasably restraining the rope 9 and consequently the weight 10 at any desired vertical position. In Figs. 6 to 10, the device may 20 comprise a pair of brake-shoe members 16 pivotally mounted on a stationary part of the device at their lower ends and disposed around the roller 8 together with the portion 25 of the rope 9 passing therearound so as to embrace the same. The shoes may be curved near their free ends to permit the rope 9 to pass freely, and also may have horizontal holes therein substantially registering with 30 each other and operatively engaged by a lever 35 17 extending through the holes and pivotally mounted on a stationary part of the device at a pin 18 between the free ends of the shoe members 16.

35 The other ends of the levers 17 at both sides of the framework extend laterally and downwardly, and are operatively connected to the 40 respective ends of an operating rod 19 extending along the bottom side of the framework 1. The rod 19 carries a member 20 secured thereto intermediate the ends. The member 20 is provided with a cam surface 21, adapted to cooperate with the inner end of a 45 handle lever 22 pivotally mounted on the frame-work bottom by means of a pin 23.

50 It will be readily seen that, with the position shown in Fig. 6 of the handle lever 22 and the rod 19, the shoe member 16 is held in its released or inoperative position, and permit the free vertical movement of the rope 9. When the handle 22 is operated to the opposite position, that is, actuated in the counter-clockwise direction, the rod 19 is pulled to 55 and held in the left hand position, forcing the lever members 17 at the respective ends in the clock-wise direction, and a braking effect is applied on the ropes 9 and the rollers 8, thus restraining the ropes 9 and consequently the weighted members 10 from their 60 vertical movements.

65 Now it is assumed that the brakes are applied on the respective ropes 9 at an intermediate height of the weighted members 10, as shown in Figs. 1, 2 and 3. Then the movable rollers 14 assume the corresponding fixed

position and become stationary. The respective ropes 13 may be considered, at present, as extending between the pair of sashes past the rollers 5, the rollers 14, stationary at present, and the rollers 7, in the order mentioned. 70 Since the sashes form counter-weights for each other, when one of them is actuated to slide upwards, the other will be lowered just the same distance with the upward movement of the former sash, and they may take positions as shown in Fig. 3.

75 In order to move both of the sashes 3 and 4 upwards or downwards simultaneously or jointly, the brake devices 15 may be released to permit free movements of the weighted members 10, and the sashes can be moved jointly to any desired height, for example, the upper-most position as shown in Fig. 4. In this case, the weighted members 10 function as the counter-weight for the both sashes 85 combined, as they are now suspended from the sash-cords 13.

80 With the suspended state of the weighted members, each sash 3 or 4 may be operated individually and it will assume any desired position independently from the other, as the weighted members will be lowered or raised half the distance travelled by the individual sash by aid of the movable pulleys 14.

85 Since the weighted members 10 are restrained from lateral movement or vertically guided by means of the stretched wire ropes 9, the sashes can slide up and down very smoothly. The tension of the rope 9 may be 90 adjusted by the screw threaded member 12 extending through the bottom portion of the member 10.

95 If desired, the weighted member 10 may be 100 made variable in weight. For this purpose, a frame or casing 30 of the member may be provided with inwardly projecting portions 31 on the opposite inner surfaces thereof, and a plurality of weights or poises 32 so formed as to interfit the projected surfaces of the frame 30 are carried within the frame 30. By changing the number of poises 32 carried 105 within the frame, the whole weight of the member 10 can obviously be varied.

110 In order to secure a positive application 115 of the brake devices 15 on the ropes 9 passing around the roller 8, the brake-shoe member 16 may have a somewhat round groove 14 in order to closely fit the rope periphery as shown in Fig. 10. The round grooves 14 can 120 also prevent unnecessary strain of the wire ropes 9.

125 In the above embodiment of my invention, I have shown the restraining device 15 as a 130 brake-shoe-type, but any other type of device may be used in substitution therefor, because the construction of the restraining device does not constitute any essential feature of my invention. For example, I may replace the device with that shown in Fig. 13 somewhat diagrammatically. The modified form 135

of restraining device comprises members 51 and 52, pivotally mounted on pins 53 and 54 which are fixed within the framework 1. The free ends of the pivoted members 51 and 52 are respectively provided with recesses oppositely registering with each other forming a space permitting the ropes 9 passing therethrough. The other ends of the levers 52 are respectively connected with rods 55, the other adjacent ends of the rods 55 being connected with a lever member 56 which may be located intermediate the lower corners of the framework 1.

The lever member 56 may be pivotally mounted on a pin 57 and a suitable operating handle, not shown, is provided for operating the lever 56 about the pin 57. The lever member 56 may be provided with angularly disposed surfaces 58 and 59 which cooperate with a spring member 60, in order to hold the lever 56 in predetermined positions after being operated in either direction.

As will readily be noted, when the lever 56 is actuated and held in the position shown, the rods 55 are held in the right hand position, and the pivoted members 51 and 52 cooperate with each other at the grooved ends to press the ropes 9 passing therebetween at the opposite sides, and the latter are restrained from vertical movement. It must be noted that when the levers 52 are turned in either direction, projections 61 provided on the levers 52 cooperate with corresponding recesses in the levers 51 formed to engage the projections 61, and the levers 51 and 52 are actuated so as to press the ropes 9 or release the same simultaneously. When the lever member 56 is turned counter-clockwise and held in the opposite position by the engagement of the surface 58 with the spring 60, the levers 51 and 52 will obviously release the ropes 9.

In Figs. 14 and 15, a modification is shown, in part, somewhat diagrammatically. In this form of my invention, the guide rope 9 in each side chamber of the framework 1 is replaced by a link structure 70. The structure may comprise a pair of levers 71 and 72, respectively pivoted in the upper and lower end portions of the weight chamber on the axes 73 and 74 respectively located therein by suitable bearing means, such as 75 and 76.

The respective ends of the levers 71 and 72 are operatively connected by a pair of vertical links 77 and 78. The lower lever 72 is provided with an arm portion, at the outer end of which one end of a rod 79 is operatively connected therewith. The rod 79 has a function and arrangement similar to the rod 19 in Fig. 6, and a similar link structure, not shown, is connected to the other end of the rod 79.

The weighted member 10' is provided with side grooves 80 and 81 adapted to receive the inner edge portions of the links 77 and 78, respectively. The member 10' carries at the

top a guide roller 14' corresponding to the roller 14 in Fig. 1, both in the disposition and function. The weight 10' is suspended by the sash-cord 13, which extends from one end secured to one of the sashes through the guide roller 5, past the rollers 14' and 7 to the other end secured to the other of the sashes.

When the rod 79 is actuated to the left, the levers 72 and 71 are turned counter-clockwise, and the links 77 and 78 are made to approach each other, thus shortening the distance therebetween, and the link edges will closely engage the grooves 80 and 81 with a sufficient pressure thereon to restrain the weighted member 10' from its vertical movements. When the rod 79 is actuated to the right, the braking action on the weighted member 10' will be released, as will be readily understood. With this arrangement, the window sashes may be operated to slide up and down either individually or jointly, and also the weighted members 10' may be properly guided by the links 77 and 78, enabling smooth operations of the sashes.

Although I have shown particular embodiments of my invention, it will be obvious to those skilled in the art that various modifications and changes may be made without departing from the spirit and scope of the invention, and I do not desire to limit the invention to the specific modifications described, but only in so far as set forth in the appended claims.

I claim as my invention:

1. A window, comprising a framework, a pair of sashes slidable up and down within said framework, a pair of weighted members, each vertically movable within one side chamber in said framework, a movable guide roller carried on each of said weighted members, a pair of stationary guide rollers mounted in the upper portion of each side chamber, a pair of sash-cords, each extending from one end secured to one of said sashes past one of said stationary rollers, said movable roller and the other stationary roller to the other end secured to the other sash, thus suspending said weighted members therefrom through said movable roller, a second pair of stationary guide rollers disposed at the upper and lower end portions of each side chamber, a rope secured to said weighted member at the ends and stretched around said second pair of stationary rollers so as to form a closed loop, a pair of pivoted lever members for each rope, having cooperating recesses in the adjacent free ends thereof between which said rope passes, and means for actuating said lever members in either direction so as to press said recessed ends to each other against said rope or release the pressure, whereby said rope may be releasably restrained from travelling.

2. A window, comprising a framework, a

pair of sashes slideable up and down within said framework, a pair of weighted members, each vertically movable within each side chamber in said framework, a movable guide roller carried on each of said weighted members, a pair of stationary guide rollers mounted in the upper portion of each side chamber, a pair of sash-cords, each extending from one end secured to one of said sashes past one of said stationary rollers, said movable roller and the other stationary roller to the other end secured to the other sash, thus suspending said weighted members therefrom through said movable roller, a second pair of stationary guide rollers disposed at the upper and lower end portions of each side chamber, a rope secured to said weighted member at the ends and stretched around said second pair of stationary rollers so as to form a closed loop, a brake device for each of said ropes, disposed around one of said second pair of rollers, and means for actuating said devices for effecting the application and release of the braking action on said ropes.

In witness whereof I affix my signature.
KITARO KATO.
